INVENTOR:

Lewis B. Weston,
By E. D. Chadwick,
ATTORNEY.

UNITED STATES PATENT OFFICE.

LOUIS B. WESTON, OF BROCKTON, MASSACHUSETTS.

MEANS FOR PREVENTING SHOES FROM TREADING OVER.

1,254,098.

Specification of Letters Patent. Patented Jan. 22, 1918.

Application filed April 24, 1917. Serial No. 164,250.

To all whom it may concern:

Be it known that I, LOUIS B. WESTON, a citizen of the United States, residing at Brockton, in the county of Plymouth and State of Massachusetts, have invented certain new and useful Improvements in Means for Preventing Shoes from Treading Over, of which the following is a specification.

The object of my invention is to provide a shoe which will resist the tendency of the ball of the foot to slide outward within the shoe and roll the upper over the outer edge of the sole while the wearer is walking. This result, which is commonly known as "treading over," is of practically universal occurrence and has the ultimate effect of permanently distorting the shoe and thereby detracting from its appearance, being particularly objectionable for that reason in the case of high grade shoes. I accomplish the object above referred to by constructing the shoe in such manner that when the wearer stands on a level surface the ball of the foot rests on a surface which slopes downward slightly from the outer side to the inner side of the shoe while the heel of the foot rests on a surface which slopes downward slightly in the opposite direction, *i. e.*, from the inner side to the outer side of the shoe, whereby the natural tendency of the ball of the foot to slide outward is resisted by a counteracting tendency of the foot as a whole to skew or turn in such direction as to move the ball of the foot inward with respect to the shoe.

In practice, the structural features which characterize my invention are preferably embodied in the inner sole of the shoe, thus producing an article of manufacture which can be sold to shoe makers and used by them in the manufacture of shoes according to the usual processes. Such an embodiment of the invention is illustrated in the accompanying drawing, in which:

Figure 1 is a plan view of one form of the inner sole with its top layer omitted;

Figs. 2 and 3 are transverse sections on the lines $x-x$ and $y-y$ respectively, Fig. 1;

Fig. 4 is a plan view of a modified form of the inner sole in process of preparation;

Fig. 5 is a transverse section showing this form of the inner sole after it has been completed, the line of section being indicated at $z-z$ in Fig. 4; and

Fig. 6 is a transverse section through the ball portion of a welt shoe containing the

inner sole represented in Figs. 4 and 5, and showing also the last on which the shoe was made.

The inner sole illustrated in Figs. 1, 2 and 3 of the drawing comprises top and bottom layers 2 and 3 which may be made of thin leather, canvas or other suitable material such as is commonly employed in inner soles, and each of which is co-extensive in area with the complete inner sole. Between the layers 2 and 3 are placed wedge-shaped inserts 4 and 5 which are preferably made of firm scrap leather and are located respectively at the heel portion and ball portion of the inner sole. The insert 4 has its maximum thickness at its inner margin, which coincides in position and outline with the inner edge of the heel portion of the inner sole, and from this margin it tapers outwardly to a thin edge. The insert 5 is thickest at its outer margin, which coincides in position and outline with the outer edge of the inner sole at the ball of the foot, and from this margin it tapers inwardly to a thin edge. In order to give its outer margin the slope which is desirable, the insert 5 may be built up at this point by super-imposing upon it a narrow strip 6 which is wedge shaped in cross-section and is tacked or otherwise secured to the insert 5, as shown in Fig. 1.

In addition to the inserts 4 and 5, an insert 7 may be placed between the layers 2 and 3 as shown in Figs. 1 and 3. This insert when employed extends longitudinally within the inner sole, preferably from about the front end of the insert 4 to the front end of the insert 5. It is thickest along its longitudinal central portion and tapers laterally in each direction to a thin edge, its outer portion being overlapped in part by the inner portion of the insert 5. All the parts above described are permanently secured together by cement or other suitable means, as in the ordinary inner sole composed of multiple layers.

It will be apparent that when the inner sole as thus constructed is embodied in a shoe the top surface of the inner sole will slope slightly downward from the outer side to the inner side of the shoe at the ball portion thereof, and from the inner side to the outer side of the shoe at the heel portion thereof, whereby the foot of the wearer will be given a tendency to skew in such direction as to counteract the tendency of the ball

- of the foot to slide outward and "tread over" the shoe. The insert 7 is not essential, but I prefer to employ it because it gives the top surface of the inner sole a configuration 5 closely conforming to the anatomy of the sole of the human foot, as shown in Fig. 3, thereby rendering the slope of said surface less noticeable to the wearer of the shoe and making the shoe more comfortable. It also 10 increases the resistance of the ball portion of the foot to the tendency to slide outward, since its thicker central portion has the effect of forming depressions in which the downwardly bulging toe joints rest. 15 As an additional means for resisting the tendency to "tread over," the inner sole may be provided at the outer edge of the ball portion thereof with an extension which forms an upturned lip in the completed shoe and 20 tends to hold the foot in place by imparting increased stiffness to the upper at this point. Such a modification is shown in Figs. 4, 5 and 6, in which the lip just referred to is formed from extensions 8 and 9 which are 25 integral with the upper and lower layers 2' and 3' respectively, the inserts 4, 5 and 7 being constructed and arranged as already described. After these parts have been assembled and secured together, as shown in 30 Fig. 4, the extensions 8 and 9 are bent into a substantially upright position and are then connected by suitable means, such as a line of stitching 10 located just above the outer margin of the insert 5. The result of 35 stitching together these extensions as just described is not only to unite them to form a lip but also to maintain them in their upright position, and when the shoe is lasted the upper 11 passes around the outside of 40 the lip thus formed, as shown in Fig. 6, and is stiffened thereby along the length of the lip. The purpose of the notches 12 and 13 formed in the extensions 8 and 9 respectively, as shown in Fig. 4, is to facilitate the 45 turning up of these extensions along the curved line which bounds the outer margin of the insert 5 and to prevent them from wrinkling when the inner sole is flexed by the act of walking, each notch being ar- 50 ranged to overlie a continuous portion of the other extension in order that no gap may exist in the completed lip.
- In manufacturing a shoe containing either form of inner sole above described, the last 55 employed should have its bottom surface shaped in accordance with the top surface of the inner sole, particularly at the ball and the heel, and that portion of the last which comes in contact with the strip 6 should be 60 cut away slightly and rounded off, the sharply-defined edge required for lasting the upper at this point being sufficiently provided by the margin of the insert 5 supported by the strip 6. A last having the contour 65 just described is shown at 14 in Fig. 6.
- In Figs. 5 and 6, which illustrate my invention as applied to a welt shoe, 15 indicates the lip or feather which is provided on the bottom of the inner sole and to which the welt is stitched. It will be understood, 70 however, that the invention is equally applicable to shoes in which the inner sole has no such lip or feather, the inner sole shown in Fig. 3 being of this type. 75
- I claim:
1. A shoe in which the foot-supporting surface slopes laterally downward from the outer side toward the inner side of the shoe at its ball portion and from the inner side to the outer side of the shoe at its heel portion. 80
  2. A shoe comprising an inner sole having its outer edge thicker than its inner edge at its ball portion and its inner edge thicker than its outer edge at its heel portion, and an upwardly-turned reinforcing lip carried 85 by the inner sole and extending longitudinally along the outer edge of the ball portion thereof, beneath the upper of the shoe.
  3. An inner sole having its outer edge thicker than its inner edge at its ball portion and its inner edge thicker than its outer edge at its heel portion, whereby its foot-supporting surface is caused to slope transversely in opposite directions beneath the ball and heel of the foot. 90
  4. An inner sole comprising upper and lower layers of thin material with inserts located between them at the outer side of their ball portions and the inner side of their heel portions, said inserts being wedge-shaped in 100 transverse section and having their thicker margins extending along the corresponding edges of the inner sole.
  5. An inner sole comprising upper and lower layers of thin material with inserts located between them at the outer side of their ball portions and the inner side of their heel portions, said inserts being wedge shaped in 105 transverse section and having their thicker margins extending along the corresponding edges of the inner sole, and a longitudinally-extending supplemental insert having a relatively thick central portion and thin lateral edges, one of said edges being overlapped by the insert at the ball portion of the inner sole. 110
  6. An inner sole having its outer edge thicker than its inner edge at its ball portion and its inner edge thicker than its outer edge at its heel portion, and also having at 120 the outer edge of its ball portion an extension adapted to form an upwardly-turned reinforcing lip. 115
  7. An inner sole comprising upper and lower layers of thin material provided along the ball portions thereof with extensions adapted to form an upwardly-turned reinforcing lip, and inserts located between said layers at the outer side of their ball portions and the inner side of their heel portions, 125 130

said inserts being wedge-shaped in transverse section and having their thicker margins extending along the corresponding edges of the inner sole.

8. An inner sole comprising upper and lower layers of thin material each provided along the ball portion thereof with a notched extension, and inserts located between said upper and lower layers at the outer side of their ball portions and the inner side of

their heel portions, said inserts being wedge-shaped in transverse section and having their thicker margins extending along the corresponding edges of the inner sole, and said extensions being turned upward and ¹² fastened together just above the edge of the ball portion to form a reinforcing lip.

Signed at Boston, Mass., this 18th day of April, 1917.

CHARLES B. WESTON.
